UNITED STATES PATENT OFFICE.

HERBERT B. GILLETTE, OF GRAND RAPIDS, MICHIGAN.

WHEEL.

Application filed May 24, 1924. Serial No. 715,573.

To all whom it may concern:

Be it known that I, HERBERT B. GILLETTE, a citizen of the United States, residing at Grand Rapids, county of Kent, State of Michigan, have invented certain new and useful Improvements in Wheels, of which the following is a specification.

This invention relates to improvements in wheels.

10 My invention relates more particularly to improvements in wheels adapted for use on trucks, although desirable and capable of various other uses.

15 The main object of this invention is to provide an improved wheel which is very strong and durable and at the same time substantially noiseless.

20 A further object is to provide an improved wheel which may be effectively formed of waste cuttings of wood.

A still further object is to provide an improved wheel which may be very rapidly and economically manufactured.

25 Objects pertaining to details and economies of construction and operation will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing forming a part of this application, in which:

Fig. I is a side elevation of a wheel embodying the features of my invention.

40 Fig. II is an enlarged detail radial section thereof.

Fig. III is a detail side elevation of the body portion prior to the mounting of clamping rings and the wheel center therein.

45 Similar reference characters refer to similar parts in all of the views.

Referring to the drawing, my improved wheel comprises an annular body portion formed of radially disposed blocks of wood, in the embodiment illustrated, consisting of the wedge-shaped blocks 1 and the rectangular blocks 2, there being a pair of wedge-shaped blocks arranged between each of the rectangular blocks. The blocks are formed or machined to provide outwardly facing shoulders 3 on which the rings 4 are secured by means of the cross rivets 5, the

rivets being preferably arranged through the rectangular blocks 2 as illustrated.

The blocks are provided with aligned tongues 6 at their inner ends, the tongues 60 being centrally disposed, and when the blocks are assembled these tongues provide an internal flange.

I provide a pair of center members 7 preferably formed of multiply wood as illustrated, each member in the structure shown consisting of six plies. These center members are a close fit in the body, being preferably forced therein under pressure, and are clamped upon the flange by means of the 70 cross rivets 8 which are preferably disposed through the tongues of the rectangular blocks. The center members are rabbeted at 9 to receive the flange.

The center members 7 are bored to receive the spindle or bearing sleeve, as may be desired, a plain bore being illustrated.

My improved wheel is very strong and rigid, and is capable of carrying heavy loads and withstanding severe racking 80 strains. It is designed to be used without a tire, so it is substantially noiseless when employed on cement floors or pavement.

The wheel may be largely made of small pieces of material which are ordinarily regarded as waste in various factories. The blocks 1 and 2 may be rapidly formed by sawing or slicing operations.

My improved wheel is preferably manufactured or assembled by the method described in my co-pending application No. 715,574 which results in economy in manufacture but in a very superior article.

Having thus described my invention what I claim as new and desire to secure by Letters Patent is:

1. In a wheel structure, the combination of a plurality of wedge-shaped blocks and a plurality of rectangular blocks disposed radially, there being a plurality of the 100 wedge-shaped blocks between each of the rectangular blocks, said blocks having outwardly facing shoulders on their sides and central aligned tongues on their inner ends coacting to provide an internal annular flange, rings clamped upon the sides of said blocks by cross rivets disposed through the rectangular blocks with the inner edges of said rings in engagement with said shoulders, and coacting center members each 105 formed of multiply wood and fitting within said blocks, their inner edges being rab-

beted to receive said internal rib, said center members being secured by cross rivets disposed through the tongues of a plurality of the rectangular blocks.

5. 2. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides and central aligned tongues on their inner ends coacting to provide an internal annular flange, rings clamped upon the sides of said blocks by cross rivets disposed through the 70 rectangular blocks with the inner edges of said rings in engagement with said shoulders, and coacting center members formed of multiply wood and fitting within said blocks and clamped upon said flange thereof 75 by cross rivets disposed therethrough.

10. 15. 3. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides and central aligned tongues on their inner ends coacting to provide an internal annular flange, rings clamped upon the sides of said blocks by cross rivets with the inner edges of said 80 rings in engagement with said shoulders, and coacting center members each formed of multiply wood and fitting within said blocks, their inner edges being rabbeted to 85 receive said internal rib, said center members being secured by cross rivets disposed through the said internal flange.

20. 25. 30. 35. 40. 45. 50. 55. 60. 65. 70. 75. 80. 85. 90. 95. 100. 105. 110. 115. 120. 125. 130. 3. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides and central aligned tongues on their inner ends coacting to provide an internal annular flange, rings clamped upon the sides of said blocks by cross rivets with the inner edges of said rings in engagement with said shoulders, their outer edges being in spaced relation to the outer edges of the blocks, and coacting center members fitting within said blocks, their inner edges being rabbeted to receive said internal rib, said center members being secured by cross rivets disposed through the said internal flange.

4. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides and central aligned tongues on their inner ends coacting to provide an internal annular flange, rings clamped upon the sides of said blocks by cross rivets with the inner edges of said rings in engagement with said shoulders, and coacting center members fitting within said blocks, their inner edges being rabbeted to receive said internal rib, said center members being secured by cross rivets disposed through the said internal flange.

5. In a wheel structure, the combination of a plurality of wedge-shaped blocks and a plurality of rectangular blocks disposed radially, there being a plurality of the wedge-shaped blocks between each of the rectangular blocks, said blocks having outwardly

wardly facing shoulders on their sides and central aligned tongues on their inner ends coacting to provide an internal annular flange, rings clamped upon the sides of said blocks by cross rivets disposed through the 70 rectangular blocks with the inner edges of said rings in engagement with said shoulders, and coacting center members formed of multiply wood and fitting within said blocks and clamped upon said flange thereof 75 by cross rivets disposed therethrough.

6. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides and central aligned tongues on their inner ends coacting to provide an internal flange, rings 80 clamped upon the sides of said blocks by cross rivets with the inner edges of said rings in engagement with said shoulders, and coacting center members formed of multiply wood and fitting within said blocks 85 and clamped upon said flange thereof.

7. In a wheel structure, the combination of a plurality of wedge-shaped blocks and a plurality of rectangular blocks disposed radially, there being a plurality of the wedge-shaped blocks between each of the rectangular blocks, said blocks having outwardly facing shoulders on their sides spaced substantially from the ends thereof and central aligned tongues on their inner ends coacting to provide an internal annular flange, rings clamped upon the sides of said blocks by cross rivets with the inner edges of said rings in engagement with said shoulders, their outer edges being in spaced relation to the outer edges of the blocks, and coacting center members formed of multiply wood and fitting within said blocks and clamped upon said flange thereof. 100

8. In a wheel structure, the combination of a plurality of radially disposed blocks conformed to provide an annular body, said blocks having outwardly facing shoulders on their sides spaced substantially from the ends thereof and aligned tongues on their inner ends, rings clamped upon the sides of said blocks by cross rivets with the inner edges of said rings in engagement with said shoulders, their outer edges being in spaced relation to the outer edges of the blocks, and coacting center members fitting within said blocks and clamped upon said tongues. 115

9. In a wheel structure, the combination of a plurality of radially disposed blocks conformed to provide an annular body, said blocks having outwardly facing shoulders on their sides and aligned tongues on their inner ends coacting to provide an internal annular flange, rings clamped upon the sides 120

of said blocks by cross rivets with the inner edges of said rings in engagement with said shoulders, and coacting center members formed of multiply wood and fitting within 5 said blocks, their inner edges being rabbeted to receive said internal rib, said center members being secured by cross rivets disposed through the said flange.

10. In a wheel structure, the combination 10 of a plurality of radially disposed blocks conformed to provide an annular body, said blocks having outwardly facing shoulders on their sides and aligned tongues on their inner ends coacting to provide an internal 15 annular flange, rings clamped upon the sides of said blocks by cross rivets with the inner edges of said rings in engagement with said shoulders and coacting center members fitting within said blocks, their inner edges 20 being rabbeted to receive said internal rib, said center members being secured by cross rivets disposed through the said flange.

11. In a wheel structure, the combination

of a plurality of radially disposed blocks 25 conformed to provide an annular body, said blocks having outwardly facing shoulders on their sides and aligned tongues on their inner ends, rings clamped upon the sides of said blocks to engage said shoulders thereof, and a pair of coacting center members 30 formed of multiply wood and fitting within said blocks and clamped upon said tongue.

12. In a wheel structure, the combination 35 of a plurality of radially disposed blocks conformed to provide an annular body, said blocks having outwardly facing shoulders on their sides and aligned tongues on their inner ends, rings clamped upon the sides of said blocks to engage said shoulders thereof, and a pair of coacting center members fit- 40 ting within said blocks and clamped upon said tongues.

In witness whereof, I have hereunto set my hand and seal.

HERBERT B. GILLETTE. [L.S.]
